UNITED STATES PATENT OFFICE.

MAX GARBELL, OF CHICAGO, ILLINOIS.

DESIGN FOR A FRAME FOR TYPEWRITING-MACHINES.

56,002.

Specification for Design.

Patented Aug. 10, 1920.

Application filed January 19, 1920. Serial No. 352,623. Term of patent 14 years.

To all whom it may concern:

Be it known that I, MAX GARBELL, a citizen of the United States, residing at Chicago, in the county of Cook and State of Illinois, have invented a new, original, and ornamental Design for a Frame for Type-writing-Machines, of which the following is a specification, reference being had to the accompanying drawing, forming part thereof.

The figure is a plan perspective view of a frame for typewriting machine, showing my new design.

I claim:

The original design for a frame for type-writing machines, as shown.

MAX GARBELL.
